UNITED STATES PATENT OFFICE.

EDWARD L. MEGILL, OF BROOKLYN, NEW YORK.

FEED-GAGE FOR PRINTING-PRESSES.

SPECIFICATION forming part of Letters Patent No. 393,480, dated November 27, 1883.

Application filed June 3, 1884. Serial No. 133,664. (Model.)

To all whom it may concern:

Be it known that I, EDWARD L. MEGILL, a citizen of the United States, residing at Brooklyn, in the county of Kings, State of New York, have invented a new and useful Improvement in Feed Gages for Platen Printing-Presses, of which the following is a specification.

My invention relates to feed-gages used on the platen of job printing-presses for registering sheets; and the object of my invention is to produce an extensible feed gage with parts arranged to slide or move lengthwise of each other and have the forward end suitably constructed to gage the sheet and the lower end pivoted at or near the edge of the platen, whereby the feed-gage is lengthened, shortened, and turned laterally and secured in various positions.

In the accompanying drawings, Figure 1 is a plan view of the platen of a printing-press with three of my feed-gages attached. The dotted lines show the sheet and feed gages transferred to different positions. Fig. 2 is an enlarged perspective view of one of the feed-gages removed from the platen. Fig. 3 is an edge view of same.

Of the printing-press, W is the platen; X, the platen-bail; Y, the platen-paper, and Z the sheet fed to the gage heads.

The sliding section A, having at the forward end a gage head, *a*, and elastic pivoted tongue *b*, is slotted through nearly its entire length, and operated upon and secured to the lower pivoted section, B, by means of a thumb-screw, *c*, and stud *d*, which pass through said slot. By omitting the stud *d* the result of lengthening and shortening the gages is still maintained, although I prefer to use the stud *d* to keep the said sections parallel. The holder or bracket C, which supports the said sections on the platen, and to which said section B is pivoted, is composed of the knee *e*, which is widened to better brace it between the bail and the platen, and is bent, as heretofore, under and around the said bail in a solid sheet or one or more narrow strips, *ff*, so that it will remain on the bail when raised

from the edge of the platen and go readily with it when pushed down again to fasten the platen-paper. The upper end of the knee *e* is folded over to form a jaw at *g*, which extends between the pivoted end of section B and the thumb screw or nut *h*.

The sliding section A (or sections, as intermediate ones may be employed) admits of a direct adjustment to and from the sheet, and may be run down about half-way between the center and the bottom edge of the platen, while the pivoted section B admits of a circular adjustment, and may be turned down so as to bring the gage-head the rest of the way to the edge. Thus, without moving the holders or extending the parts far beyond the platen, the distance is covered from center to bottom edge. By the combined movement of the sliding and pivoted sections with the holders, by sliding and turning the former and moving the latter along the platen-bail, the gage-head may be brought to any spot on the lower half of the platen, and by tightening them with the screws a rigid hold is insured. The screws, however, may be omitted where friction alone will be sufficient to hold the parts in position.

Any form of device for pivoting the feed-gage at the edge of the platen may be employed, and the parts may be connected by any suitable arrangement.

The side guides may be secured by either the upper or lower platen-bail.

What I claim is—

1. An extensible feed-gage consisting of parts sliding or moving lengthwise of each other, and having the forward end constructed to gage the sheet and the other end pivoted at or near the edge of the platen, substantially as herein described.

2. The combination of the gage-head *a*, tongue *b*, slotted section A, screw *c*, lug *d*, and pivoted section B, all arranged substantially as herein described.

EDWARD L. MEGILL.
